WINGED PIPE PLUG

David H. Pomroy, 805 Merrett Drive,
Pasadena, Calif. 91104

Filed Oct. 6, 1966, Ser. No. 4,174

Term of patent 14 years

(Cl. D91—3)

FIG. 1.

FIG. 2.

FIG. 3.

FIG. 1 is a top plan view of a winged pipe plug showing my new design;

FIG. 2 is an elevational view thereof; and

FIG. 3 is another elevational view taken from a position 90 degrees from that of FIG. 2.

I claim:

The ornamental design for a winged pipe plug, as shown.
